UNITED STATES PATENT OFFICE.

THOMAS L. FAWICK, OF WATERLOO, IOWA.

TRACTOR.

1,267,525.

Specification of Letters Patent. Patented May 28, 1918.

Application filed December 26, 1916. Serial No. 138,999.

To all whom it may concern:

Be it known that I, THOMAS L. FAWICK, a citizen of the United States of America, and a resident of Waterloo, Blackhawk 5 county, Iowa, have invented certain new and useful Improvements in Tractors, of which the following is a specification.

My invention relates to improvements in tractors, and the object of my improvement 10 is to provide a frame and housing for the mechanism of a tractor, having a minimum number of parts, and associated and connected together in the most convenient manner to insure proper functioning, combined 15 with ease in assembling and disassembling.

This object I have attained by the means which are hereinafter described and claimed, and which are illustrated in the accompanying 20 drawings, in which Figure 1 is a plan view of my improved tractor frame and housing for the mechanism thereof, with parts removed or broken away; Fig. 2 is a side elevation of the same, with the addition of certain mechanical elements, and 25 Fig. 3 is a detail view of the housing-seat for the boxing of the steering-gears.

Similar numerals of reference denote corresponding parts throughout the several views.

30 Referring to the drawings, the numeral 1 denotes the U-shaped frame of a tractor, formed from a bent channel-bar, or bar of any other desired cross-section. A cross-beam 2 connects the members of said frame 35 a little forward of their middles, and has its ends secured thereto by bolts 15. This cross-beam may be or not be integral with the motor-housing 3, but is preferably cast integral therewith in order to insure proper 40 rigidity and prevent any relative movement between the parts under the shocks of use.

The rear part of the motor-housing 3 has oppositely-directed horizontal lugs or arms 4 mounted and secured fixedly upon the rear 45 ends of the members of the frame 1 by means of bolts 16.

Upon the rear open face of the motor-housing 3 is secured a housing 5 to contain the clutch-mechanism, said housing 5 having 50 an integral rearward extension 6 containing the transmission-gearing, as also a chamber 9 for the driving-gears of a transverse shaft carrying a belt-wheel 12, said shaft being seated in a lateral boxing 11 of said housing. Said housing also contains a chamber 10 to receive worm or other gearing form-

ing part of the driving-mechanism for the shaft 14 of the traction-wheels 20. The housing-part 10 has oppositely-directed hollow parts 13, which serve to receive the axles 60 14, and the terminal part of the housing-part 10 is in the form of an integral cylindrical casing for a friction-drum brake.

On one side of the housing-part 6 is a laterally-directed open seat 7 upon which is 65 secured a housing 8 adapted to receive the steering-gears of the steering-wheel shaft 18.

The forward part of the U-shaped frame 1 may be supported on one or more carrying wheels (not shown) suitably connected 70 operatively with the steering-mechanism of the tractor.

In this application I do not particularly show, nor do I claim, special features of the mechanism of the tractor, preferring to reserve such for other applications, but confine 75 myself to the new and improved frame and housing structures therefor.

The U-shaped frame 1 is not only less expensive to construct than multi-part frames, 80 but is more durably rigid, yet of minimum weight consistent with its strength.

The motor-housing 3 is in one piece, and so strongly mounted on and connected to the frame 1 at widely separated locations as 85 to be able to resist the rudest shocks without relative displacement, and has a minimum number of openings or joints, which renders it practically dust-proof.

The other housing-part 5—6—10, and the 90 steering-gear boxing 8 are so aligned relatively to the motor-housing as to make one rigid casing for all the mechanism of the tractor, easily assembled or disassembled, and having large openings to permit inspection, removal or repair of the elements of the mechanism, without necessity of demounting any part of the housing itself.

The boxing 19 for the band-brake, also the boxing 8 for the steering-gear are in 100 free communication with oil-filled parts of the housing 6—10, which insures complete lubrication of the moving parts therein. This obviates any necessity for independent lubrication of the steering-gear.

It is also to be understood that considerable variations or modifications of the parts of my improved device may be effected, without, however, departing from the principles of my invention, or from the scope of its 110 protection.

Having described my invention, what I

claim as new, and desire to secure by Letters Patent, is—

1. In combination, a U-shaped frame, a housing for mechanism rigidly mounted on the members of said frame, and alined communicating housing-compartments for other connected mechanism in communication with said housing and mounted on the rear part of said first-mentioned housing rigidly.
  2. In combination, a U-shaped frame, and alined housing-parts for moving mechanism mounted on said frame in medial alinement therewith to extend rearwardly therefrom, said housing having laterally-directed housing - compartments for laterally-directed mechanisms operatively connected to the mechanism in the main housing.
  3. In combination, a frame, a housing to independently receive a motor mounted thereon, another single-piece housing rigidly secured to the rear part of said motor-housing opening directly therewith and having compartments adapted to receive clutch-mechanism, transmission-gearing, belt-wheel gearing, and traction-wheel mechanism, in the order named, and a boxing removably secured to the latter housing opening directly therewith and adapted to receive steering-gear elements.
  4. In combination, a housing to independently receive a motor, another housing for
- mechanism mounted rigidly upon said motor-housing in communication therewith, and a steering-gear boxing mounted upon one side of said second-mentioned housing, 35 said boxing and housing having registering openings.
5. In combination, a housing to independently receive a motor, another housing for mechanism mounted rigidly upon said motor-housing in communication therewith, a steering-gear boxing mounted upon one side of said second-mentioned housing, and a bearing-box for a belt-wheel shaft mounted upon the opposite side of said second-mentioned 45 housing, both said boxings having openings and said housings having openings registering therewith.
6. In combination, a hollow housing for moving mechanism, and a boxing to contain 50 steering-gear elements detachably secured thereto and in communication therewith, said housing and said boxing being formed to receive and retain a communicating supply of a fluid lubricant immersing said mechanisms.

Signed at Waterloo, Iowa, this 23d day of December, 1916.

THOMAS L. FAWICK.
